UNITED STATES PATENT OFFICE.

STANLEY M. RATLIFF AND WILLIAM L. PAYNE, OF NORWOOD, OHIO.

AUTOGRAPHIC REGISTER.

1,267,452.

Specification of Letters Patent.

Patented May 28, 1918.

Application filed July 28, 1917. Serial No. 183,222.

To all whom it may concern:

Be it known that we, STANLEY M. RATLIFF and WILLIAM L. PAYNE, citizens of the United States, residing at Norwood, Hamilton county, Ohio, have invented certain new and useful Improvements in Autographic Registers, of which the following is a specification.

This invention comprehends improvements in that class of registers, generally known as autographic registers, in which a casing incloses one or more stores of strip paper which may be drawn under a wicket in the casing over a tablet so as to permit the paper to be written upon, the strips of paper being then withdrawn from the casing, or coiled up into a record-roll within the casing, or one strip withdrawn and torn off as used, while the other strip is coiled up within the casing.

The improvements will be readily understood from the following description taken in connection with the accompanying drawings in which:—

25 Figure 1 is a side elevation of a register embodying an exemplification of our improvements:

Fig. 2 a side elevation of the casing, removed:

30 Fig. 3 a plan of the register:

Fig. 4 an end elevation of the register, at its discharging end:

Fig. 5 a side elevation of the register with the casing and finger-piece absent, and with 35 the platen partially elevated:

Fig. 6 a vertical longitudinal section of the register in the plane of line *a* of Figs. 3, 4 and 8:

40 Fig. 7 a diagrammatic showing of the run of the papers, parts of the register appearing in the same vertical longitudinal section as in Fig. 6:

Fig. 8 a plan of the register, the casing being absent, and parts appearing in horizontal 45 section in the plane of line *b* of Figs. 1 and 6:

Fig. 9 a plan of portions of the embossing rolls:

50 Fig. 10 an elevation of the driving clutch of the storage roll:

Fig. 11 a rear side elevation of the gearing actuating the storage roll:

Fig. 12 a front side elevation of the free end of the pivoted platen: and

Fig. 13 an elevation of a portion of the 55 countershaft.

The figures of the drawings are upon a diversity of scales.

Registers of the general class to which our improvements relate, are sometimes arranged to deal with a single strip of paper from which the records of transactions are torn one by one; but it is the more usual custom to provide for duplicating the record being made, the apparatus providing for 65 the supply of a plurality of papers. In a very common use of machines of this class, one supply of paper will provide the paper which is to be torn off, for instance, as sales bills to be given to customers. For the sake 70 of convenience, we will refer to this paper as the "bill paper", and the individual transactions entered upon it as the bills. The paper on which the duplicate record is made we will call the "record paper", and the 75 roll from which this paper is drawn will be called the "record supply roll", while the roll into which it is wound will be called the "record storage roll".

While we illustrate our improved register as carrying but two strips of paper, the considerations above set forth may be applied, in a general way, to the machine when arranged to deal with any plurality of papers.

80 In the drawings:—

1, indicates a base:

2, two pairs of sidewise open bearings projecting up from the base at the end of the general register opposite its discharging 90 end:

3, a similar bearing near the discharge end of the machine and provided with a side opening:

4, a pair of bearings with their common 95 axis disposed near and parallel with the axis of bearing 3:

5, a bearing in alignment with bearing 3:

6, pivots supported by the base near one of its ends:

7, a skeleton frame extending over the above-mentioned bearings and having its heel mounted on the pivots 6:

8, a writing tablet or platen carried by

the frame and having an upwardly presenting surface:

9, a casing disposed over and secured to the base and adapted to house the mechanism mounted on the base:

10, lugs supported fixedly by the base and adapted to enter suitable apertures in the end wall of the casing when the casing is in place:

10, 11, a lock and key arrangement disposed at the end of the apparatus opposite the lugged end and serving to prevent the displacement of the casing from the base:

12, a wicket through the roof of the casing, 15 over the tablet, this wicket providing for writing being done upon paper lying on the tablet, and the relationship of the under surface of the roof of the casing to the upper surface of the tablet being such as to permit the presence of the papers and to permit of the clamping of those papers when the platen and casing are approached relative to each other:

13, the supply roll of bill-paper:

25, 13', the supply roll of record paper:

14, the spindle for the bill-supply roll 13, this spindle being mounted in one pair of the bearings 2, this spindle having a flange near one of its ends, inwardly of the bearing supporting that end:

15, a flange removably loose on the opposite end of the spindle:

16, the hub of this flange, the same projecting outwardly and engaging in the appropriate one of the bearings 2:

17, springs supported by the base and engaging peripheral grooves in the spindle 14 on the side corresponding with the open side of bearings 2:

40, 18, the spindle for the record-supply roll 13', this spindle being mounted in the second pair of bearings 2 and being provided with flanges and retaining springs, as has been described in connection with spindle 14:

45, 19, the removable flange of spindle 18:

20, the spindle for the record storage roll, this spindle being supported by the bearings 3 and 5, and being diametrically slotted to receive the end of the strip of record 50 paper which is to be rolled up, this slot extending to and out of one extreme end of the spindle:

55, 21, a removable flange for spindle 20, at that end of the spindle which is open by reason of the presence of the slot, the hub of this flange engaging the open bearing 3:

22, a gear at the end of spindle 20 opposite the end which bears the removable flange:

60, 23, a hub for this gear, the same being mounted for rotation in bearing 5 and having its inner surface provided with an axial socket and with a convex inner face having an open diametrical groove, the end of

spindle 20, opposite the end having the loose flange, engaging loosely within the socket of the hub:

24, a diametrically disposed pin carried by the end of spindle 20 and adapted, when the end of the spindle engages the socket in hub 23, to loosely engage the slot in the face of the hub:

25, a plurality of rolls, three being illustrated, journaled in the free end of the platen-frame 7, and preferably geared together, 75 with their axes parallel with the spindles which have been mentioned, the peripheries of these rolls being contiguous to each other and being, at least as regards a coöperating pair of them, provided with embossing surfaces adapted to effect the embossment of paper passing between the rolls, the illustration, in Fig. 9, illustrating the peripheries of all of the rolls as being provided with embossing surfaces formed by nurling:

26, that portion of the roof of the casing at the discharge end of the register, this portion being higher than the balance of the roof of the casing and having an outwardly convex cross-section, this portion of the roof of the casing being disposed over the group of rolls 25:

27, a slot through this elevated roof-portion of the casing, and extending widthwise of the casing, and having a length somewhat in excess of the width of the papers to be dealt with:

28, a strut carried by the frame 7 to the rear of the tablet and being, preferably, disposed at an angle so that its upper edge is nearer the tablet:

29, a slot through this strut and having a length somewhat in excess of the papers being dealt with:

30, a guide-rod or roll carried by the tablet-frame between the strut and the rear end of the tablet and having its upper surface about level with the tablet:

31, a similar guide-rod or roll carried by the tablet-frame to the rear of the strut:

32, the strip of bill-paper, passing from its supply-roll 13, which is mounted on spindle 14, over the guide-rod 31, between the tablet and the wicketed portion of the roof of the casing, through the group of rolls 25, and out through the slot 27, which slot provides a tearing edge:

33, a portion of the bill-paper withdrawn outwardly through slot 27 and adapted to be torn off:

34, a record storage roll, wound on spindle 20:

34', the strip of record paper, passing from its supply-roll 13', over the guide-rod 30, between the tablet and the bill-paper thereover, between a pair of the rolls 25, and then to its storage-roll 34:

- 35, a piece of carbon paper having its heel end extending through the slot 29 in the strut, and extending over the strut and tablet:
- 5 36, a countershaft journaled in bearings 4:
- 37, a fingerpiece fast on this countershaft, exterior to the casing and adapted to serve in oscillating the shaft:
- 10 38, a gear loose on the countershaft and engaging gear 22:
- 39, a ratchet fast on the countershaft, outwardly of gear 38:
- 15 40, a spring-pawl carried by gear 38 and engaging the ratchet:
- 41, a stop-pawl serving to prevent the backward movement of the ratchet as the pawl retreats:
- 20 42, an upward projection from shaft 36, and adapted to engage under cam-shaped surfaces carried by the free end of the tablet-frame, so that when the countershaft is in normal angular condition the tablet will be pressed upwardly so as to clamp the papers between the platen and the wicketed roof of
- 25 43, the casing, this projection being illustrated as a wire bail having its body extending along the countershaft and having its ends secured fixedly in the shaft:
- 30 44, a spring coöoperating with the countershaft and adapted to urge projection 42 to its upper position and the fingerpiece 37 to its lower position:
- 35 45, a fixed stop adapted to limit the turning of the countershaft in either direction, the illustration showing this stop as being formed by a pin carried by one of bearings 4 and adapted to be engaged by the bail 42: and
- 40 46, a blade spring pivoted at its heel, shown as being pivoted on the countershaft, the free portion of this spring having a perforation engaging the front end of the record storage spindle 20 and preventing the displacement of the spindle from bearing 3.
- 45 When the register is loaded and ready for use, it contains the two supply-rolls of paper and the carbon paper, threaded as has been indicated, the loading and threading, being, of course, done while the casing is absent
- 50 and the tablet frame turned upward. Oscillations of the fingerpiece serve, in an obvious manner, to draw the record paper forward and wind it up on the record storage roll, advancing movement being given to the papers
- 55 to any extent desired. Thus, at each use of the machine, the papers may be advanced a distance represented by individual bill-blanks formed by the bill-paper; or the bill-paper may be blank and at each use of the
- 60 machine the papers may be advanced such distance, constant or varying, as corresponds with the notations to be made upon the bill-paper. The bill-paper is torn off, when desired, at slot 27, the lower portion of which
- 65 is throated, the concave contour of the slot-
- ted portion of the roof of the casing providing somewhat acute tearing edges at the walls of the slots.
- As the record-paper is pulled through the machine, by the winding action of the record storage roll, it pulls the bill-paper along with it by reason of the friction between the two papers and by reason of the feed-roll action of rolls 25 which are forced to turn by the dragging action of the record paper. When the heel end of the piece of carbon paper is put through the slot 35 in the strut and the paper then turned down over the record paper, it is found in practice that the heel of the carbon paper is held so securely as to resist any displacing action by the movement of the paper strips, the movement of which simply tends to nicely smooth out the carbon paper by reason of the fact that it is held at its rear end while it is free at its forward end. 70
- Spring 43 causes the tablet to be normally pressed upwardly so as to clamp the edges of the papers nicely around the margins of the wicket and prevent the papers being shifted by the hand or by the action of the writing implement. When the writing has been done and the fingerpiece is moved to advance the strip papers, its first action is to release the platen from its clamping office, thus permitting the papers to move freely. When the casing is in place it is held by the lock and lugs, thus preventing unauthorized opening of the casing to give access to the stored record, and preventing the rising of the casing under the influence of the upwardly pressed platen. 75
- The running of the papers through the rolls 25 embosses the papers after the writing has been done and prevents, to a very large degree, the possibility of altering any writing on the papers. The embossing to be produced may be of any set character, such as would be produced by uniformly knurled rolls, or the embossing may be in the form of raised lettering or designs for advertising effect. As the paper runs between a pair of rolls to receive its embossing, one roll of the pair acts as a counter for the other roll, the embossing pressure taking place against the counter roll, and while a mere nurling of both rolls of the pair is satisfactory and preferable, it is not essential that the periphery of the counter roll of the pair bear any nurling or the like, 100 as the single embossing roll will produce a more or less satisfactory local distortion of the substance of the papers when coöperating with a hard or soft counter-roll with a plain periphery, and at the same time have such aggressive contact with the papers as to cause the bill-strip to be dragged along with the record-strip. If the carbon paper be double-faced then the writing will appear on the front and back of the bill-paper 105
- 110
- 115
- 120
- 125
- 130

and this, taken in connection with the embossing of the written paper, renders it extremely difficult to make unauthorized alterations in the bill.

5 Assuming that it be desired to load the empty register, the casing being absent and the tablet-frame being turned up, by pressing the rolls 15 and 19 to the right, against the resistance of springs 17, the two empty 10 rolls, to call them such, may be removed from their bearings; their loose flanges may be removed; supply-rolls of paper may be placed on the spindle and the loose flanges replaced; and the two full rolls may then 15 be placed in their bearings, by first flexing the springs 17 forwardly, the springs then engaging the grooves in the spindles, thus preventing the spindles from becoming displaced from their bearings, and the springs 20 being prevented from becoming displaced outwardly sidewise. The strip from the record supply roll is then passed up over the guide 30 and the tablet and through the embossing-rolls on the upturned tablet-25 frame, and then down and into connection with the slotted storage spindle 20.

The tablet-frame is then to be turned down to working position and the carbon paper is to be applied as has been indicated, 30 after which the bill-paper is to be threaded in proper course and the cover applied.

When the register is opened for the purpose of removing the record-roll, spring 45 is sprung sidewise thus permitting one end 35 of the storage roll to be swung rearward free of its bearing, the opposite end of the spindle of the roll being then freely disengageable from its clutch connection with hub 23, all gearing being thus left undis- 40 turbed when the storage-roll is removed. By removing the loose flange from the removed storage-roll the record-roll may be readily pulled from the spindle, whereupon the empty spindle, with its loose flange re- 45 placed, may be restored to its working position.

We claim:—

1. An autographic register comprising, a tablet, a wicketed casing over the tablet, the 50 casing and tablet being relatively movable and adapted to receive freely and to clamp papers between them, an agent normally urging the casing and tablet toward each other, and manually operative means for 55 rendering said agent inactive, combined substantially as set forth.

2. An autographic register comprising, a tablet, a wicketed casing over the tablet, the casing and tablet being relatively movable 60 and adapted to receive freely and to normally clamp papers between them, a spindle for a record storage roll, a finger-piece operatively connected with said spindle for turning it, and operative connections between 65 the finger-piece and the tablet for permitting

moving the tablet relatively away from the casing while the spindle is turning forwardly, combined substantially as set forth.

3. An autographic register comprising, a tablet, a wicketed casing over the tablet, the 70 casing and tablet being relatively movable and adapted to receive freely and to normally clamp papers between them, a spindle for a record storage roll, a fingerpiece for turning said spindle, and mechanism 75 connected with the fingerpiece and serving to permit the separation of the tablet from the casing, combined substantially as set forth.

4. An autographic register comprising, a 80 wicketed casing, a tablet frame disposed thereunder and having pivotal support at one end, a tablet carried by the tablet-frame, a spring urging the tablet and casing into normal clamping relationship, and means 85 for rendering said spring inactive combined substantially as set forth.

5. An autographic register comprising, a wicketed casing, a tablet-frame disposed thereunder and having pivotal support at 90 one end, a tablet carried by the tablet-frame, a spring urging the tablet toward the casing, and hand-operated mechanism for rendering said spring inactive so as to permit the moving of the tablet in the direction away 95 from the casing, combined substantially as set forth.

6. An autographic register comprising, a removable wicketed casing, a tablet disposed thereunder, a pivotally supported tablet-frame carrying the tablet, and a strut carried by the tablet-frame at the initial end of the tablet and provided with a slot extending lengthwise of and entirely through it for the heel of a piece of carbon paper, 100 combined substantially as set forth.

7. An autographic register comprising, a removable wicketed casing, a tablet disposed thereunder, a pivotally supported tablet-frame carrying the tablet, a strut carried by the tablet-frame at the initial end of the tablet and provided with a slot for the heel of a piece of carbon paper, and co-operating rolls carried by and moving with the tablet-frame at the terminal end of the tablet, combined substantially as set forth.

8. An autographic register comprising, a base, a pair of supply-rolls supported thereby, a record storage-roll supported by the base, a tablet supported by the base above the level of the rolls, and a pair of embossing rolls supported below the tablet in position to engage the pair of papers coming over the tablet from the supply-rolls, 115 combined substantially as set forth.

9. An autographic register comprising, a base, a pair of supply-rolls carried thereby, a record storage-roll carried thereby, a tablet-frame pivoted to the base, a tablet carried by the tablet-frame above the level of 120

the rolls, and embossing rolls carried by the free end of the tablet-frame and adapted to engage the pair of papers coming from the supply-rolls regardless of the angular position of the tablet-frame, combined substantially as set forth.

10. An autographic register comprising, a wicketed casing, a vertically vibratable tablet disposed under the wicket, an oscillatory shaft, a finger-piece for oscillating the shaft, and a projection from the shaft engaging the tablet and adapted to bring about the vibrating of the tablet as the fingerpiece is actuated, combined substantially as set forth.

15. 11. An autographic register comprising, a wicketed casing, a vertically vibratable tablet disposed under the wicket, an oscillatory shaft, a fingerpiece for oscillating the shaft, a projection from the shaft engaging the tablet and adapted to bring about the raising and lowering of the tablet as the fingerpiece is actuated, and a spring urging the projection into a position to hold the tablet in its raised position, combined substantially as set forth.

25. 12. An autographic register comprising, a wicketed casing, a vertically vibratable tablet and tablet frame disposed thereunder, a shaft, a finger-piece for oscillating the shaft, and a bail-wire having its body extending along but some distance from the shaft and adapted to engage the tablet-frame and having its ends bent at right angles and secured in the shaft, and a spring urging the bail to active position, combined substantially as set forth.

30. 13. An autographic register comprising, a pair of bearings, a record storage roll spindle carried thereby, a gear connected with the spindle, a countershaft, a gear loose thereon and engaging the first-mentioned gear, pawl and ratchet mechanism connecting said loose gear and the countershaft, a fingerpiece connected with the countershaft, 45 a supply-roll, and a tablet supported above the level of the rolls and adapted to support the paper on its way between the rolls, combined substantially as set forth.

40. 14. An autographic register comprising, 50 a bearing, a hub journaled in the bearing

and having an axial socket in its inner face, a gear fast on said hub, an open-sided bearing in line with the first-mentioned bearing, a storage-roll spindle having one end supported by the open-sided bearing and having its other end loosely engaging said socket, a clutch connection between the hub and the end of the spindle engaging its socket, a supply-roll, and a tablet supported above the level of the rolls and adapted to support the paper on its way between the rolls, combined substantially as set forth.

55. 15. An autographic register comprising, a bearing, a hub journaled in the bearing and having an axial socket in its inner face and provided with a diametrical groove, a gear fast on said hub, an open-sided bearing in line with the first-mentioned bearing, a storage-roll spindle having one end supported by the open-sided bearing and having its other end loosely engaging said socket, a pin crossing the socket end of the spindle and engaging the groove in the hub, a supply-roll, and a tablet supported above the level of the rolls and adapted to support the paper on its way between the rolls, combined substantially as set forth.

60. 16. An autographic register comprising, a bearing, a hub journaled in the bearing and having an axial socket in its inner face and provided with a diametrical groove, a gear fast on said hub, an open-sided bearing in line with the first-mentioned bearing, a storage-roll spindle having one end supported by the open-sided bearing and having its other end loosely engaging said socket, a pin crossing the socket end of the spindle and engaging the groove in the hub, a blade-spring provided with a perforation 65 engaging the end of the spindle supported by the open-sided bearing, a supply-roll, and a tablet supported above the level of the rolls and adapted to support the paper on its way between the rolls, combined substantially as set forth.
